(57) **CLAIM**

We claim the ornamental design for a desk, as shown and described.

DESCRIPTION

FIG. 1 is a perspective view of a desk in a lowered position. FIG. 2 is a top plan view of the desk depicted in FIG. 1. FIG. 3 is a bottom plan view of the desk depicted in FIG. 1. FIG. 4 is a right side elevational view of the desk depicted in FIG. 1.

FIG. 5 is a left side elevational view of the desk depicted in FIG. 1.

FIG. 6 is a front elevational view of the desk depicted in FIG. 1.

FIG. 7 is a rear elevational view of the desk depicted in FIG. 1.

FIG. 8 is a perspective view of the desk of FIG. 1 in a raised position.

FIG. 9 is a top plan view of the desk depicted in FIG. 8.

FIG. 10 is a bottom plan view of the desk depicted in FIG. 8.

FIG. 11 is a right side elevational view of the desk depicted in FIG. 8.

FIG. 12 is a left side elevational view of the desk depicted in FIG. 8.

FIG. 13 is a front elevational view of the desk depicted in FIG. 8; and,

FIG. 14 is a rear elevational view of the desk depicted in FIG. 8.

1 Claim, 8 Drawing Sheets
